UNITED STATES PATENT OFFICE

AUGUST BRUNS, OF JAMAICA, NEW YORK

AWNNG

Application filed November 15, 1929. Serial No. 407,440.

My invention relates to a new and improved awning.

One of the objects of my invention is to provide an improved awning which can be combined with a window frame so that the awning can be readily manipulated.

Another object of my invention is to provide an awning which can be conveniently wound up to be housed in the upper part 10 of the window frame, and which can be conveniently extended to occupy a number of different positions.

Another object of my invention is to provide an awning device which can be applied 15 to the frame of a window and which can be readily caused to project from the window frame and which can be caused to rigidly extend from the window frame in a series of regulated positions.

Another object of my invention is to provide a simple and efficient device which can be readily manufactured and assembled with a window frame.

Other objects of my invention will be 25 set forth in the following description and drawings which illustrate a preferred embodiment thereof, it being understood that the above general statement of the objects of my invention is intended to merely generally explain the same and not to limit it in any manner.

Fig. 1 is a front elevation.

Fig. 2 is a sectional view on the line 2—2 of Fig. 1.

Fig. 3 is a sectional view on the line 3—3 of Fig. 1.

Fig. 4 is a section along the line 4—4 of Fig. 2.

Fig. 5 is a section along the line 5—5 of Fig. 4.

Fig. 6 is a section along the line 6—6 of Fig. 4.

Fig. 7 is a detail sectional view similar to Fig. 2, but showing the awning in its upper or inoperative position.

The device is applied to any ordinary window having a frame F, a lower window sash 1, and an upper window sash 2. The awning A, which is made of any suitable flexible material is wound upon a roller com-

prising a metal tubular portion 4 having solid wooden inserts 5 at each end thereof. The wooden inserts 5 may have a drive fit within the tubes 4, being provided with reduced ends 5a for this purpose. The awning material A is connected to the outer ends of the wooden inserts 5 by means of tacks or screws 6. The outer ends of the wooden inserts 5 are provided with recesses into which the ears 7a of discs 7 fit. These ears 7a of the disc 7 are connected by means of screws 8 to the wooden inserts 5. Each disc 7 is provided with a bearing pin 9. Each bearing pin 9 fits turnably in a threaded bushing 10. The threaded bushing 10 is provided with one-piece washer and lock nut 11 which are both internally threaded so that they can be screwed upon the external threading of the shank of the bushing 10 to firmly clamp the bushing against the wall 12. Similar means are used to connect the other bearing pin 19 of the roller to the member 4 and to the other guide 12. The roller is thus held at the upper end of frame F, so that it is free to turn. As shown in Fig. 3, a sprocket 14 is connected to the bearing pin 9, because the other pin 19 merely turns freely without being positively actuated. The sprocket 14 is provided with a chain 15 by means of which the sprocket 14 can be turned in either direction. The chain 15 is connected to a lower sprocket 16 which is mounted upon a bearing pin 17. Said bearing pin 17 is held to a wall of the guide 12 by means of a bushing 10a which corresponds to the bushing 10 and by means of a combination lock nut and washer device 11a which corresponds to the device 11. The lower bearing pin 17 is provided with a handle 18 which is connected thereto by means of a set screw. The handle 18 is provided with a manipulating head 21 which is part of a pin 20 that can slide transversely or horizontally with respect to the handle 18. The pin 20 is provided with a groove 22 and a pin 23 is provided in the outer end of the handle 18 which limits the transverse sliding movement of the pin 20. The inner end of the pin 20 can enter a stop member 24, which forms an extension of bushing 100.

10a, in order to hold the handle 18 locked in position, when this is desired. Vertically movable slides 26 are located adjacent the guides 12. These slides 26 are provided with recesses 27, and tongues 28 are formed of the metal which has been bent back to form said recesses 27. Said tongues 28 make sliding contact with the adjacent surfaces of guides 12. As clearly shown in Fig. 6, the main bodies of the slides 26 have slidable contact with the front surfaces of the inner walls of the guides 12, and the tongues 28 make slidable contact with the rear surfaces of said inner walls. Likewise, the tops of the slides 26 are provided with transversely bent ears 29 which hold a bar 30. The awning fabric A passes around the bar 30 and the end of the awning fabric passes around the outer end or arm 32 of the U-shaped bar 31 whose inner end is provided with a series of openings 33 through which the pin 20 is adapted to pass, so that the arm 31 can be held at a number of different angles. By pulling the pin 20 outwardly, it is released from the arm 24 and from the arm 32, and then the arm 31 can be adjusted to any desired angle so that the corresponding hole 33 is engaged by the pin 20 when the pin 20 is pushed inwardly.

30 When it is desired to wind up the awning, the parts are moved to the position shown in Fig. 7. In this position, each slide 26 is at the upper end of the corresponding guide 12. In the wound-up or inoperative position, the awning is located within a protective hood 36. The inner and laterally bent ends of the U-shaped arm 31 are inserted through suitable openings in the slides 26, so as to provide a pivotal connection. As shown in Fig. 5, the inner walls of the fixed guides 12 are provided with enlarged openings 30a through which the bushings 10 and 10a can be passed so that these parts can be moved up and down to their proper position in which position they are then clamped.

40 Each of the slides 26 is provided with an opening 35 at the lower end thereof. As clearly shown in Figs. 4 and 7, tongues 28 are provided at the upper and at the lower 50 end of each slide 26 in order to efficiently guide the sliding movement of each said slide.

55 In order to move the awning to the operative position shown in Fig. 2, it is merely necessary to pull upon the head 21 so as to release the pin 20 from the stop member 24 and from the arm 32. Upon turning the handle 18, the chain 15 is actuated so as to turn the awning roller in the direction 60 in which the slides 26 are permitted to descend.

65 The downward movement of the left-hand slide 26 shown in Fig. 4 is limited by the stop 28a, with which the lower tongues 28 of said slide 26 contact. The corresponding

tongues 28 of the right-hand slide 26 then contact with the top of the member 24. Of course, the pin 20 is pulled into its inoperative position while the handle 18 is being turned to cause the slides 26 to descend. 70 When the slides 26 have descended to their lowest position, further movement of the handle 18 causes the U-shaped bar 31 to turn to the extent desired. When the pin 20 is pushed inwardly, it engages the hole 75 35 of the adjacent slide 26 and it also engages one of the holes 33. In this position, the slides are firmly held against upward movement, and the member 31 is held against tilting movement. Hence, the device is very 80 stable in case of a high wind. Likewise, the upper part of the awning acts as a shade, while the lower part of the awning projects outwardly.

85 I have shown a preferred embodiment of my invention, but it is clear that numerous changes and omissions could be made without departing from the spirit of my invention.

90 I claim:

1. In an awning device, a roller having flexible awning material connected thereto, means adapted to manipulate said roller so as to wind or unwind the awning material, a pair of guides associated with said roller, said guides having slots in their adjacent walls, slides movably associated with said adjacent walls, and pivoted means connected to said slides and having the end of the awning material connected thereto, said slides having tongues slidably associated with the inner surfaces of said adjacent walls. 95

100 2. An awning device comprising a roller, having awning material connected thereto, a pair of guides associated with said roller, said guides having their adjacent walls provided with slots, a pair of slides associated with said guides, the bodies of said slides being adjacent the outer surfaces of said adjacent walls, said slides having tongues slidably contacting with the inner surfaces of said adjacent walls, said slides also having tongues at their upper ends, a crossbar connected to said tongues and around which the awning material passes, and pivoted means connected to said slides and having the outer end of the awning material connected thereto. 110

115 3. An awning device comprising a roller, a pair of slides associated therewith, pivoted means connected to said slides and having the end of the awning material connected thereto, means adapted to actuate said roller and comprising a turnable handle, and stop means connected to said pivoted means and adapted to cooperate with said handle to hold said pivoted means at a predetermined angle. 120

125 4. An awning device comprising a roller, 130

a pair of slides associated therewith, pivoted means connected to said slides and having the end of the awning material connected thereto, means adapted to actuate said roller and comprising a turnable handle, and stop means connected to said pivoted means and adapted to cooperate with said handle to hold said pivoted means at a predetermined angle, said handle having a laterally slidable pin and said pivoted means having a locking sector adapted to cooperate with said pin.

5. In an awning device, the subcombination of a pair of guides having adjacent walls provided with slots, a roller having bearing means, said bearing means being clamped to the slotted walls of said guides by means of cooperating threaded members respectively located within and without said 10 guides, said slots having enlarged portions through which said locking members located within said guides can be inserted.

6. An awning device of the type adapted to be connected to a window frame, said device having awning material wound upon a roller, a pair of vertical hollow guides adapted to be connected to said window frame, the adjacent walls of said guides being vertically slotted, slides associated 15 with said slotted walls, the bodies of said slides being adjacent the outer surfaces of said slotted walls, and said slides having inwardly bent tongues which slidably contact with the inner surfaces of said adjacent walls, said slides having tongues at their upper ends, a cross-bar connected to said tongues, a pivoted bar connected to said slides below said cross-bar, the awning material which is connected to said roller passing 20 around said cross-bar and being connected to said pivoted bar, a turnable pin mounted in one of said guide members, means connecting said pin and said roller so that they turn in unison, a handle connected to said 25 pin, the head of said handle forming part of a laterally slidable locking pin, said pivoted bar having a perforated sector having holes adapted to cooperate with said locking pin.

50. In testimony whereof I affix my signature.
AUGUST BRUNS.
